CLAIM

I claim the ornamental design for a watch case, as shown and described.

DESCRIPTION

FIG. 1 is a top view of the watch case showing my new design in a first embodiment;

FIG. 2 is a bottom view thereof;

FIG. 3 is a right side view thereof;

FIG. 4 is a left side view thereof;

FIG. 5 is a front view thereof;

FIG. 6 is a rear view thereof;

FIG. 7 is a top view of the watch case in a second embodiment in which all other views are the same as in the first embodiment; and,

FIG. 8 is a top view of the watchcase in a third embodiment in which all other views are the same as the first embodiment.

The broken line showing of numerals in FIG. 8 is for illustrative purposes only and forms no part of the claimed design.
